CLAIM

The ornamental design for an electronic computer, as shown and described.

DESCRIPTION

FIG. 1 is a top, front and right side perspective view of an electronic computer showing my new design;
FIG. 2 is a top plan view thereof;
FIG. 3 is a bottom plan view thereof;
FIG. 4 is a front elevational view thereof;
FIG. 5 is a rear elevational view thereof;
FIGS. 6 and 7 are respectively left and right side elevational views thereof, the keyboard in the pulled out position;
FIG. 8 is a right side elevational view thereof, the display panel and keyboard in the closed position;
FIG. 9 is a top, front and right side perspective view thereof, the keyboard in the pulled out position;
FIG. 10 is a front elevational view thereof, the display panel and keyboard in the closed position; and,
FIG. 11 is a top plan view thereof, the display panel and keyboard in the closed position.
